UNITED STATES PATENT OFFICE.

ARTHUR W. McCURDY, OF VICTORIA, BRITISH COLUMBIA, CANADA.

METHOD OF PRODUCING AUGERS.

Application filed May 20, 1920. Serial No. 382,994.

To all whom it may concern:

Be it known that I, ARTHUR W. McCURDY, a subject of the King of England, residing at Victoria, British Columbia, Canada, have invented certain new and useful Methods of Producing Augers, of which the following is a specification.

This invention pertains to an improved method of forming twisted blades for the production of augers. Broadly considered the invention may be said to comprise the production of a spirally twisted blade from flat bar stock and in employing means for holding the stock by its edges only as it is forced through the die and brought to the desired spiral conformation. Another step pertains to the carbonization of the spirally twisted blade prior to its final finishing. To produce such spirally twisted stock I preferably employ a die the interior of which is provided with two oppositely disposed spiral slots, the pitch of the slots decreasing toward the discharge end of the die, or, if desired, the spiral formation may be obtained by using a plurality of dies successively, the dies being graduated so as to partially twist the stock in succession so that the stock will ultimately emerge from the last die with the spirals at an angle of substantially 33° to the transverse axis.

In the accompanying drawings, I have shown in Fig. 1 an embodiment of a die and a die holder employed in the process of twisting the stock prior to its being welded to the auger shank, provided with the cutting lips, carbonized, and finally sharpened, in Fig. 2 a side elevation of an auger constructed in accordance with my invention, and Figure 3 a transverse sectional view illustrating the manner in which the stock is held by its edges.

No claim is made herein to the die nor to the apparatus whereby the stock may be forced through the die, as that forms the basis of my copending application Serial No. 382,993 filed on or about the 20th day of May, 1920, nor is any claim made herein to the particular form of cutting and chisel lips, as they form the basis of my application filed on or about July 9, 1919, Serial No. 309,556.

In the drawings, (Fig. 1), 1 denotes the die body having two oppositely disposed spiral slots 2 and 3 formed therein, the spiral in the instant case being shown as gradually

decreasing in pitch to the line A—A where it assumes an angle of 33° , and such angularity is continued from that point on to the discharge end of the die.

In practice, the die is mounted in a holder, 60 the body of which is denoted by 4, and from which extends a tubular extension 5, said extension being provided with a pair of oppositely disposed straight slots 6 and 7, the lower ends of which are in alinement 65 with the mouths of the slots 2 and 3 formed in the die. A hollow plug 8 is screwed into the lower end of the body of the holder and abuts the lower end of the die forcing the same upwardly in the holder against a 70 shoulder 8^a, set screws 9 and 10 being likewise employed to assist in holding the die firmly in place and to prevent rotative action thereof as the blank is forced through the die. A plunger or ram 11, operated 75 through any suitable source of power, stands in alinement with the bore of the die and bears against the end of the flat bar or stock which is to be forced through the die. Any suitable mounting for the die may be 80 employed.

A plurality of separate or abutting dies may be employed in which the spiral grooves gradually diminish in pitch until they come to the 33° angle.

In operation I take machine steel, which has a low carbon content, as compared to tool steel, and place a section of it, in a cold condition, in the guide formed in the tubular extension. The ram is then brought 90 against the end of the stock and the stock is forced endwise through the straight grooves in the extension and through the spiral grooves in the die, the ram following the blank until it is completely ejected from 95 the die. It will be noted that the die contacts the blank at its edges only. In other words, the stock is held by and at its edges only, and consequently friction is reduced to a minimum. This results in a material 100 saving of power. It has been found that the stock is not deformed except that at its forward end it is slightly rounded and emerges from the die in the form of a true spiral with the desired degree of angularity. 105 Inasmuch as the ram is of a diameter less than that of the width of the stock it may pass freely through the tubular guide and likewise through the die so that the stock is entirely discharged from the die and 110

there is no occasion to open the die or make it in sections longitudinally so that stock can be removed therefrom.

The blank after being thus produced is welded to a shank 12 and has a floor lip cutter 13 formed upon one twist of the spiral and a chisel cutter 14 formed upon the land of the opposite spiral, as indicated in Fig. 2. It is also counterbored to form a socket for the reception of a removable center pin 15, after which the structure is carbonized, the degree of carbonization preferably being such as to leave the center of the stock unaffected. The auger is then polished and the final edge finish is given to the floor lip and chisel cutters. Thus an auger is produced which has a fine grained hardened surface and a relatively soft and tough center throughout its body. Such treatment is all sufficient for my purposes as the cutting edge of the floor lip cutter and the chisel or scoring cutter, the latter being in effect a continuation of the land of one of the spirals, are formed in that portion of the body which is hardened and tempered.

From the foregoing it will be seen that a mild machine steel may be employed and worked cold, points of economy both as to initial cost and facility of working. Where the ordinary cutter formation is em-

ployed or is to be produced the twisted blade may be carbonized throughout.

What is claimed is:

1. That method of producing a spirally twisted blade from flat bar stock, which consists in forcing the stock into and through a die having two oppositely disposed spiral grooves, the edges only of the stock engaging the grooves. 35

2. That method of producing a spirally twisted blade from flat bar stock, which consists in entering the end of a bar into a pair of oppositely disposed spiral grooves formed in a die with the body of the bar intermediate the edges left unsupported and cut of contact with the die, and thereafter forcing the blade through the die by end-wise pressure exerted upon the blade. 45

3. That method of producing an auger 50 blade of the double twist type from flat bar stock, which consists in forcing the blade through a die having a pair of oppositely disposed spiral grooves of gradually decreasing pitch, the edges alone of the 55 blade engaging the grooves with the body of the blade out of contact with the walls of the grooves and die.

In testimony whereof I have signed my name to this specification.

ARTHUR W. McCURDY.
